UNITED STATES PATENT OFFICE

133,724

DESIGN FOR AN ELECTRIC SOLDERING DEVICE

Benjamin P. McKinley, Chicago, Ill.

Application June 14, 1941, Serial No. 101,472

Term of patent 14 years

To all whom it may concern:

Be it known that I, Benjamin P. McKinley, a citizen of the United States, residing at the city of Chicago, in the county of Cook and State of Illinois, have invented a new, original, and ornamental Design for an Electric Soldering Device, of which the following is a specification, reference being had to the accompanying drawing, forming a part thereof, in which

Figure 1 is a side elevational view of an electric soldering device in an adjusted position showing my new design,

Figure 2 is a view looking at the top of Figure 1, and

Figure 3 is an elevational view looking from the right at Figure 1.

The characterizing features of my design for the soldering iron disclosed, reside in a handle member of the specific configuration shown, connected to the heating element barrel by a hinge and bracket member of the specific shape shown in the drawing.

I claim:

The ornamental design for an electric soldering device, as shown and described.

BENJAMIN P. MCKINLEY.
